John Lally, Inventor

By his Attorney

Robert B. Stillgore

UNITED STATES PATENT OFFICE.

JOHN LALLY, OF BOSTON, MASSACHUSETTS.

BUILDING CONSTRUCTION.

1,258,917.

Specification of Letters Patent. Patented Mar. 12, 1918.

Application filed April 18, 1917. Serial No. 162,948.

To all whom it may concern:

Be it known that I, JOHN LALLY, a citizen of the United States, and resident of Boston, in the county of Suffolk and State 5 of Massachusetts, have invented certain new and useful Improvements in Building Constructions, of which the following is a specification.

My invention relates to improved building 10 construction of the reinforced concrete type and it is my object to produce a column and floor structure which will be fireproof, have great strength, light weight, simple design, 15 easy of erection and occupy much less space than the older forms of construction with the joints between superimposed columns made inside the floors so that there is no reduction in floor area over that occupied by the cross-section of the column itself.

20 In the drawings Figure 1 is a view, partly in section, of my improved structure; Fig. 2 a top view of a round crown frame and Fig. 3 a top view of a square crown frame.

25 My construction comprises a filled tubular column 1 extending from a base plate 2 to the upper part of the floor 3 with a plate 4 on the lower end of the superimposed column 5 to make the connection between the two columns 1 and 5.

30 This column 1 is filled with concrete 6 as well as being surrounded with it.

A bracket 7 extends through a slot in the upper part of the column 1 into the concrete filling as shown in Fig. 1. A strut 35 8 extends from the bracket 7 to a cross T-beam 9 with its web lying in slots cut in the upper edge of the column 1.

There are a plurality of these brackets 7, struts 8 and T-beams 9 as indicated in 40 Figs. 2 and 3 and the T-beams are anchored by countersunk bolts 10 set in the flange and extending into the concrete filling in the column 1. The T-beams are preferably welded together at their junction to make 45 a solid, one piece top for the crown.

An outer frame 11 for the crown may be secured to the outer ends of the struts 8 and may be circular as shown in Fig. 2 or square as shown in Fig. 3, or any other 50 desired form, and to which the ends of the carrying bars 12 for the floor may be attached or the carrying bars may be run over

the head as shown at 12' or the two methods may be combined as shown.

The plate 4 is anchored to the upper 55 column 5 by means of anchor bolts 13 running through it and embedded in the concrete filling thereof. The top column 5 is also anchored to the T-beams 9 by the bolts 14 so that one column is tied to the 60 other making a continuous shaft of metal without a break and all connections are made inside the floor where they do not encroach on the floor space.

The structure is finally completely embedded in concrete as shown in Fig. 1 which concrete is integral with the floor concrete making a reinforced monolith construction.

By this design and construction I obtain 70 a strong, light and fireproof building which may be of several stories in height and reduce the space occupied by the crown to such an extent that a crown 12 inches square will have the strength and carrying capacity of one 24 inches square of the older 75 construction.

I claim:—

1. Building construction comprising a hollow column, a plastic filling therein, said column being slotted intermediate of its 80 ends and at its upper edge, brackets in the intermediate slots extending into the plastic filling, T-beams in the upper slots, struts extending from the brackets to the T-beams, a frame surrounding the outer ends of the 85 T-beams and secured thereto and a plastic covering for the whole.

2. Building construction comprising a hollow column, a plastic filling therein, said column being slotted intermediate of its 90 ends and at its upper edge, brackets in the intermediate slots extending into the plastic filling, T-beams in the upper slots, struts extending from the brackets to the T-beams, a frame surrounding the outer ends of the 95 T-beams and secured thereto, carrying bars secured to the crown thus formed and a plastic covering for the whole extending into and forming part of the floor of the building.

3. Building construction comprising a hollow column, a plastic filling therein, said column being slotted intermediate of its ends and at its upper edge, brackets in the

intermediate slots extending into the plastic filling T-beams in the upper slots, means for securing the T-beams together at their common meeting points, struts extending from the brackets to the T-beams, a frame surrounding the outer ends of the T-beams and secured thereto and a plastic covering for the whole.

Signed at Boston, in the county of Suffolk and State of Massachusetts this 9th 10 day of April, A. D. 1917.

JOHN LALLY.
